UNITED STATES PATENT OFFICE.

CHARLES R. STORZ, OF BROOKLYN, NEW YORK.

SCISSORS.

1,339,797

Specification of Letters Patent. Patented May 11, 1920.

Application filed September 12, 1919. Serial No. 323,232.

To all whom it may concern:

Be it known that I, CHARLES R. STORZ, a citizen of the United States, and a resident of the city of New York, borough of Brooklyn, in the county of Kings and State of New York, have invented a new and Improved Scissors, of which the following is a description.

My invention relates to scissors and is 10 adapted for embodiment in scissors generally, it having particular advantages when embodied in surgical scissors.

The general object of the invention is to provide a scissors with removable cutting 15 blades and a practical means for securing the blades immovably in position on the scissors and providing for the convenient placing and removing of the blades. Advantages of the separate blades are that they 20 can be replaced by a pair of new blades for approximately the cost of resharpening of a common pair of scissors. Also, material for the blades may be used that has the highest cutting qualities and which for 25 technical reasons cannot be used for the body of the scissors not only because of its high cost but because of its liability to be injured in the drop forging and other processes by which the body of the scissors is 30 ordinarily produced. Also, by repeated sharpenings, the ordinary scissors loses its shape which is a distinct detriment in the case of surgical scissors. Also, with the provision of separate blades the main members 35 of the scissors may be made of rustless or stainless steel which is an important consideration in the case of surgical scissors requiring repeated boiling and sterilizing, it being well known on the other hand that 40 rustless steel does not lend itself to the making of cutting members.

The nature of my invention and the advantages will more clearly appear from the specific description following.

Reference is to be had to the accompanying drawings forming a part of this specification, it being understood that the drawings are merely illustrative of one example of the invention.

Figure 1 is a plan view of a pair of scissors provided with my removable blades;

Fig. 2 is a plan view of the front portion of one of the scissors members with the removable blade thereon;

Fig. 3 is a view similar to Fig. 2 with the blade omitted;

Fig. 4 is a plan view of the removable blade;

Fig. 5 is a cross section on line 5—5, Fig. 1;

Figs. 6, 7 and 8 are cross sections respectively on the lines 6—6, 7—7, and 8—8, of Fig. 2.

In producing a practical embodiment of my invention, the handled scissors members 10 of any desired form are pivoted by any approved means, the pivot means shown being known as the French pivot and involving a headed stud 11 on one member and a correspondingly shaped opening 11^a in the other member so that the members may be disconnected when in a particular angular relation.

The detachable blade 12 provided for each member 10 presents a hole 13 to accommodate the stud 11. Each member 10 at the blade seat has undercut recesses 14, 15 there-in at different distances from the end and blade 12 has correspondingly inclined tongues 16, 17. The undercutting of the recesses and the angularity of the respective tongues 16, 17 are reversed. Said tongues serve to snugly fasten the blade in position by entering the front tongue 16 in the front undercut recess 14 and then moving the blade 12 in its own plane laterally until the second tongue 17 snaps into its recess 15. In order to further provide against the possible looseness of the blade and to positively guard against its displacement, I provide a turnable locking element 18 on each member 10 at the blade seat and rearward of the recess 15, said elements being flush with, or within the planes of said seats, each of said elements being swiveled and having a head flat at one side or otherwise formed to give it an eccentric or cam form. Adjacent to each element 18 and complementary to the hole in which it turns is a recess 19 in the blade seat, said recess being adapted to receive a lug 20 on the blade 12 so that when said lug is in position and element 18 turned, said element will bear laterally against said lug and firmly bind against the same to positively lock the blade against movement.

The above described construction provides a practical means for insuring firmness of the blade in position as well as permitting it to be placed and removed with facility. The separate character of the blade permits perfect freedom in the selection of the material such as high carbon steel to give the

desired cutting edge and similarly, complete freedom of choice is permitted in the selection of materials for the handle members that will not be impaired by the usual process of manufacturing scissors.

The blades or cutter elements 12 are resilient so that they will yield to bending pressure for permitting the tongues 16, 17 to be entered into place in recesses 14, 15 by a turning movement of the blade in its general plane and while the rear end is flexed upwardly so that the rear tongue 20 clears screw 18 in the entering of the tongues 16, 17, after which the blade resumes its flat unflexed form against its seat, the tongue 20 snapping downwardly into its recess 19. It will be observed that the blades 12 and the seats therefor on the integral cutting members forming the front end of the scissors beyond the pivot overlie each other so that a portion of one blade always lies over the other, regardless of the angular relation of the scissors members in the cutting action or in other words that the blades lie over or against each other during the movements of the blades within the range of the cutting so that the overlapping relation of the blades at all times is such that the one blade holds the other against any tendency to lift from its seat, the arrangement making it necessary to swing the scissors members through an arc beyond the largest arc through which they move in cutting before the blades can release themselves or be released.

I would state in conclusion that while the illustrated example constitutes a practical embodiment of my invention, I do not limit myself strictly to the mechanical details herein illustrated, since manifestly the same can be considerably varied without departure from the spirit of the invention as defined in the appended claims.

Having thus described my invention, I claim:

1. A scissors presenting cutter seats having undercut recesses therein at different distances from the front ends of said seats, and removable cutter elements adapted to said seats and having inclined tongues receivable in said recesses.

2. A scissors presenting cutter seats each having an undercut recess, and removable cutter elements adapted to said seats and having transversely inclined tongues receivable in said recesses.

3. A scissors presenting cutter seats having therein recesses at different distances from the front ends of the seats, and re-

versely undercut, and removable cutter elements adapted to said seats and having reversely inclined tongues receivable in said recesses.

4. A scissors presenting cutter seats having therein recesses at different distances from the front ends of the seats, and reversely undercut, and removable cutter elements adapted to said seats and having reversely inclined tongues receivable in said recesses, said cutter elements being resilient.

5. A scissors presenting cutter seats each having a recess therein, a turnable locking element on each member at the recess, and removable blades adapted to said seats and each having a tongue receivable in the adjacent recess, said tongues being engageable by said locking elements by turning the latter.

6. A scissors presenting cutter seats each having a recess therein, a turnable locking element on each member at the recess, said elements having cam surfaces, and removable blades adapted to said seats and each having a tongue receivable in the adjacent recess, said tongues being engageable by said cam surfaces by the turning of said locking elements.

7. A scissors presenting cutter seats having undercut recesses therein at different distances from the front ends of said seats, removable cutter elements adapted to said seats and having inclined tongues receivable in said recesses, and a turnable locking element on each member, there being a recess in said member at said locking element and said cutter elements each having a tongue receivable in that recess adjacent to the turnable element to be engageable by said turnable element.

8. A scissors including members presenting cutter seats at the opposed faces thereof, each seat having an undercut recess therein, removable cutter elements adapted to said seats and having each an inclined tongue receivable in the recesses of the respective seats, a turnable locking element on each member at the seat thereof, said seats having each a second recess directly adjacent to the respective locking elements, and said cutter elements having each a second tongue receivable in the last-mentioned recesses of the respective seats, said locking elements being adapted by the turning thereof to engage the second-mentioned tongues when the latter are in the last-mentioned recesses.

CHARLES R. STORZ.
